COLLAR CAN AND METHOD OF MAKING
SAME

Charles J. Aulbach, Syracuse, N. Y., assignor to
Continental Can Company, Inc., New York,
N. Y., a corporation of New York

Application December 8, 1932. Serial No. 646,325

3 Claims. (Cl. 113—120)

The invention relates to new and useful improvements in a collar can, and the method of making the same.

An object of the invention is to provide a collar can wherein the inserted collar is held in the can through the gripping action of an outwardly rolled bead at the lower end of the collar having the raw edge thereof contacting with and biting into the wall of the can.

10 A further object of the invention is to provide a method of producing a collar can of the above type wherein the collar may be freely inserted in the can without unduly straining the same, and wherein the lower edge portion is brought into 15 gripping contact with the can body wall by a forming die after the collar is placed.

In the drawing which shows by way of illustration one form of collar can and the method of making the same—

20 Figure 1 is a sectional view showing the formed collar partly placed in the container preparatory to the seating and fixing of the collar in the can;

25 Fig. 2 is a sectional view through the collar and can body and the dies used for seating the collar and shaping the lower end portion of the collar for contact with the walls of the can, and

30 Fig. 3 is a sectional view through the finished can with the collar inserted and with an end secured thereto.

The improvement in the collar can will be first described, and then the method of forming the same. The collar can consists of a body portion 1 preferably of cylindrical form, to which a can end 2 is secured by a double seam 3. The wall of the can body is provided with a score line 4 and also a score line 5 setting off a tearing strip with the usual projecting tongue on which a key may be placed for rupturing the metal along the score lines, and thus disconnecting the end from the body portion.

35 Disposed within the can body is a collar 6 having a portion 7 intermediate the upper and lower edges thereof which contacts with the body wall below the lower score line 5. The collar is so dimensioned as to have a frictional grip on the body wall in this region. The collar above the portion 7 is inset, and at the upper edge portion is rolled inwardly as indicated at 8 so as to strengthen the upper edge of the collar and form a smooth edge. The can end 2 in the present embodiment of the invention has a depressed portion 9 forming a depending collar which lies 40 between the inserted collar 6 in the body wall

and serves as a reclosing means after the rip strip has been torn away.

The new feature of the collar can resides in the means for holding the collar in place in the can body. The can body wall is preferably formed without a bead therein. The lower portion of the collar is bent inwardly at 10 and thence outwardly at 11 with the upwardly extending portion so arranged that the raw edge of the metal will contact with the inner surface of the wall of the can body. The outwardly bent portion is preferably die-formed after the collar is inserted in the can body, and the raw edge of the metal is forced into firm gripping contact with the wall of the can body. The edge is so disposed that it will hold the collar from either an inward or outward movement in the can body. When the cover is replaced for reclosing the can, it is often pressed hard against the cover, and unless the collar is firmly seated, it will be dislodged or shifted inwardly. Furthermore, this embedded engagement of the edge of the collar in the wall of the can forms a connection so that the contents of the can will not leak by the edge, but must pass through the collar when it is dispensed from the can.

45 The collar when inserted in the can by my improved method, has this lower edge portion die formed after the collar has been initially placed in the can body. The lower edge portion 6^a of the collar is initially formed so that it is substantially in line with the upper inset portion 6^b of the collar. In fact, the collar is initially formed of a diameter approximately that indicated at 6^a and 6^b, and the portion therebetween 50 is offset outwardly for contact with the wall of the can. By shaping the collar this way, the offset portion contacting with the can may be dimensioned so as to make just the desired frictional contact with the can.

55 There are advantages in the flanging of the can body at the same time when the collar is seated therein. By shaping the collar as described above, it may be readily inserted in the can body before said can body is flanged, as shown in Fig. 1 of the drawing. The inset portion 6^a will slip into the can body, and the inclined wall leading to the offset portion which contacts with the can body wall will direct the collar into the can body. The collar may be 60 very easily pressed into the can body to the extent shown in Fig. 1. It is then submitted to forming dies, as shown in Fig. 2 of the drawing. The upper die member 12 is provided with a depending portion 13 inset from the outer edge 65

of the die, and the die is curved as indicated at 14, so as to roll the edge of the wall of the can body outwardly into a flange which is indicated at 15. The die also has a flat portion 16 which 5 contacts with the collar and forces the collar into the can body at the time when the flange 15 is formed. This insures that the upper edge of the collar will be located a uniform and a predetermined distance from the top edge of the 10 flange so that when the end 2 is placed on the can, said end will contact with the top edge of the collar. This gives a maximum capacity for the can. The can may be filled practically to the top edge of the collar, and this is to a very 15 slight distance below the inner face of the can end 2. When the tearing strip is removed, there will be no spilling of the contents, as the can has capacity when the tearing strip is removed for the entire content sealed in the can.

20 There is also a lower die member 17 which may be used for flanging the lower edge of the can body. Said die member 17 has an extending portion 18 which is curved at 19 for die shaping the lower edge portion of the can body wall. The 25 flange formed is indicated at 20. There is a limiting wall 21 which determines the length of the flange formed at the bottom of the can. This serves also as an abutment to prevent endwise movement of the can body when the collar is 30 being forced into the can body by the upper die member. If it were not for this limiting wall, the flanges might lack uniformity, due to the fact that at the same time the upper flange is formed, the collar is forced into frictional engagement with the can wall by the downward pressure of the upper die member. The lower die member 17 is provided with a curling surface 22. The portion 6^a of the collar passes along the vertical wall 23 of the die member 17 and is 35 brought into engagement with this curling surface 22, which rolls the lower edge portion of the collar outwardly and forces the raw edge of the metal into biting contact with the inner wall of the can body. This edge may be embedded in the wall of the can body to a slight 40 extent, so as to make a very tight joint between the collar and the can body, preventing leakage of the contents of the can past said gripping line. Furthermore, this gripping contact 45 between the lower edge of the collar and the can wall will firmly hold the collar from any endwise movement in the can body, particularly when the cover is placed on as a re-closure, and pressure is applied through the cover against the 50 collar tending to force it into the can body.

55 From the above it will be apparent that I have provided a collar can which is very simple in construction and wherein the collar is very firmly seated through the gripping contact between the lower edge of the collar and the wall of the can.

60 I have also provided a very simple method of

producing this collar can, wherein the collar is forced into the can without undue frictional contact between the two, and is finally seated by die-shaping the lower edge portion to bring it into contact with the wall of the can. Furthermore, by my improved method, the flanges may be formed on the can body at the same time that the collar is seated and attached thereto, and this will lock the collar a predetermined distance from the formed flange at the upper end of the can body. While it is preferred to form the flanges when the collar is seated, it will be understood that the invention may be applied to the placing and seating of a collar by a forming die in the can body on which the flanges have already 90 been formed.

Having thus described the invention, what I claim as new and desire to secure by Letters-Patent, is—

1. A can comprising a cylindrical body having score lines forming a tearing strip, a collar within said body overlying the region of the tearing strip, said collar having the central portion thereof in frictional engagement with the can body, and the lower portion thereof spaced inwardly 100 away from the can body and bent outwardly and upwardly into said space so as to cause the raw edge of the metal forming the collar to contact with and grip the wall of the can body, said can body above and below the collar and in the region 105 thereof being of uniform diameter and free from inwardly and outwardly projecting portions.

2. The method of making a rip strip collar can consisting in forming a cylindrical can body, inserting a formed collar into said can body overlying the rip strip which collar is dimensioned so as to have frictional gripping contact with the body wall intermediate the upper and lower edge portions of the collar, die-curling the lower edge portion of the collar outwardly and upwardly so 115 as to cause the extreme lower edge portion of the collar to grip the wall of the can body while maintaining said can body below the collar and in the region of the collar of uniform diameter.

3. The method of making a rip strip collar can 120 consisting in forming a cylindrical can body, inserting a formed collar into said can body overlying the rip strip which collar is dimensioned so as to have frictional gripping contact with the body wall intermediate the upper and lower edge 125 portions of the collar, die-curling the lower edge portion of the collar outwardly and upwardly so as to cause the extreme lower edge portion of the collar to grip the wall of the can body while maintaining said can body below the collar and in the 130 region of the collar of uniform diameter, and die-flanging the upper edge of the can body after said collar has been inserted and simultaneously with the curling of the lower edge of the collar.

135 CHARLES J. AULBACH.
